UNITED STATES PATENT OFFICE.

THOMAS H. SYMINGTON, OF BALTIMORE, MARYLAND.

JOURNAL-BOX LID.

SPECIFICATION forming part of Letters Patent No. 739,517, dated September 22, 1903.

Application filed March 24, 1903. Serial No. 149,369. (No model.)

To all whom it may concern:

Be it known that I, THOMAS H. SYMINGTON, a citizen of the United States of America, and a resident of 1169 Calvert Building, Baltimore, Maryland, have invented certain new and useful Improvements in Journal-Box Lids, of which the following is a specification.

My invention relates to certain new and useful improvements in journal-boxes, and particularly to the construction of the lid therefor; and the particular object of my invention is to provide a lid of the hinged type which will rest firmly on its seat all the way round and which will be held tightly to the seat, whereby the lid will form a dust-tight cover for the box. The form of lid shown in this application is a modification of that shown and described in my application, Serial No. 142,609, filed February 9, 1903.

With these objects in view the invention relates to certain constructions and combinations of parts, the preferred form of which will be first particularly described and the invention pointed out in claims.

Referring to the drawings, wherein like parts are represented by the same reference-numeral wherever they occur, Figure 1 is a side elevation of a journal-box, partly in section, showing my lid applied thereto. Fig. 2 is a front view of the box, partly in section. Fig. 3 is a detailed view of the spring which holds the lid either open or closed.

1 designates a journal-box of any desired type provided with the usual opening in its front, the opening having the seat 2 running round the same, on which the lid 3 is adapted to rest.

4 4 are a pair of ears suitably spaced apart and preferably formed integral with the box. 40 I have shown these ears as extending up from the top of the box; but it is to be understood that these ears could be placed at the sides or bottom of the box, if desired, without departing from my invention.

45 The lid 3 is provided with a pair of ears 5 5, preferably and as shown at the upper corners of the lid, and 6 is an elongated opening passing through the ears, by which the lid is pivoted to the box. The purpose of 50 having this opening elongated will be herein-after described. It will be understood that

the ears on the box may be inside and those on the lid outside, if preferred.

7 is a bolt passing through the ears 4 and 5 and on which the lid swings. As shown, 55 this bolt is provided at one end with a head 8 and at the other end with a slot through which the cotter-pin 9 is passed to hold the bolt in place. Pivoted on the bolt between the ears 5 5 is an arm 10, the arm or lever having a head 11, provided with an opening through which the bolt 7 passes, and this head is provided with a flat portion 12. Immediately in the rear of the head 11 I provide on the box a projection 13 of proper shape to receive and hold the coil-spring 14. This spring is composed, preferably, as shown, of two coils 15, connected by a central tongue 16, the free ends 17 of the wire forming this spring being adapted to enter holes in the 7c rear portion of the projection 13, the coils 15 of the spring 14 resting against the curved back portion 18 of the projection 13 and the tongue 16 bearing against the head 11 of the arm 10. When the box is in the closed position, as shown in Fig. 1, the tongue rests against flat portion 12 of the head 11, and when the box is opened the spring will rest against the portion 19 of the head and hold the lid raised.

20 is a lug provided near the center of the 80 cover 3 within the area of the seat and under which the outer free end of the arm 10 engages. By this construction it will be seen that the spring 14 will hold the lid 3 to its seat when the box is closed, as shown in Fig. 85 1, and will hold the lid up when the box is opened. Because of the elongated opening this lid is free to move toward and away from its seat without interference by the pivot-bolt 7. Hence when the pressure is exerted on the 90 center of the lid by the arm 10 the pressure will be equally distributed upon the seat all way round, and this equal distribution of the pressure will not be interfered with by the pivot-bolt, whereas if the opening in this lid-lug was the size of the bolt the bolt would support the lid on one side and might prevent its contact with the seat on the pivot side.

While I describe what I believe to be the preferred form of my invention, I desire to have it understood that many modifications and mechanical changes might be made

therein without departing from the spirit of my invention.

Having thus described my invention, what I claim as new, and desire to secure by Letters 5 Patent, is—

1. The combination with a journal-box of a lid hinged to the box, an arm hinged to the box on the same pivot by which the lid is hinged, a spring mounted on the box and bearing at one end on the arm and adapted to hold the lid to its seat, the pressure of the spring being exerted on the lid through the arm only at a point within the area of the seat.
- 15 2. The combination with a journal-box, provided with a seat, of a lid hinged to the box, a lever pivoted on the box having one end bearing on the lid within the area of the seat, a spring mounted on the box having one end secured to the box and the other end bearing against the other end of the lever.
- 20 3. The combination with a journal-box

provided with a seat, of a lid hinged to the box, a lever pivoted on the box having one end bearing on the lid within the area of the seat, a coiled spring mounted on the box having one end secured to the box and the other end bearing against the other end of the lever.

4. The combination with a journal-box provided with a seat, of a lid hinged to the box, a lever pivoted on the box having one end bearing on the lid within the area of the seat, a double coiled spring connected by a central tongue, the disconnected ends of the spring being secured to the box and tongue 35 of the spring being adapted to bear against the other end of the lever.

Signed by me at Baltimore, Maryland, this 17th day of March, 1903.

THOMAS H. SYMINGTON.
